CLAIM

The ornamental design for an automotive wheel front face, as shown and described.

DESCRIPTION

FIG. 1 is a left perspective view of the automotive wheel front face, showing my new design;

FIG. 2 is another perspective view thereof;

FIG. 3 is a right perspective view thereof;

FIG. 4 is a front view thereof;

FIG. 5 is a reduced left perspective view thereof; and,
FIG. 6 is a reduced right side view thereof.

The broken line showing of the KONIG logo, the rectangular indentation and the outer rim is for illustrative purposes only and forms no part of the claimed design.
